UNITED STATES PATENT OFFICE.

ANDREW J. WATSON, OF MARTINSVILLE, ASSIGNOR OF ONE-HALF TO ISAAC FECHHEIMER, OF TERRE HAUTE, INDIANA.

SHAFT-SUPPORT.

SPECIFICATION forming part of Letters Patent No. 393,946, dated December 4, 1888.

Application filed August 28, 1888. Serial No. 284,007. (No model.)

To all whom it may concern:

Be it known that I, ANDREW J. WATSON, a citizen of the United States, residing at Martinsville, in the county of Morgan and State 5 of Indiana, have invented certain new and useful Improvements in Shaft-Supports, of which the following is a specification.

My said invention relates to that class of devices by which the shafts or poles of vehicles are supported at an elevation when not 10 in use; and it consists in an improved construction whereby cheapness and efficiency are secured, all as will be hereinafter more particularly described and claimed.

Referring to the accompanying drawings, which are made a part hereof, and on which similar letters of reference indicate similar parts, Figure 1 is a perspective view of a vehicle-axle and a pair of shafts secured 15 thereto in the ordinary manner and provided with my improved shaft-support; Fig. 2, a longitudinal sectional view of the same, showing the shaft-support in side elevation; Fig. 3, a view similar to Fig. 2, except that the shafts 20 are secured in elevated position; Fig. 4, a top or plain view of the shaft-support as seen when looking downwardly thereon when in the position shown in Figs. 1 and 2; Fig. 5, a view looking toward the left from the dotted line 25 5 5 in Fig. 3; Fig. 6, a detail view through the two points of the shaft-support when they come together, looking upwardly from the dotted line 6 6 in Fig. 3; and Fig. 7, a detail section on the dotted line 7 7 in Fig. 5.

In said drawings the portions marked A represent an axle to a vehicle; B, the shafts thereto; C, a whiffletree mounted on the cross-bar B' to said shafts; D, the portion of the shaft-support which is secured to the axle, and 30 E the portion which is secured to the cross-bar B'.

The axle, shafts, their cross-bar, and the whiffletree are or may be all of the ordinary or any desired construction, and will not be 45 further described herein, except incidentally in describing the invention.

The support portion D, which is secured to the axle, is in the main a blade-like device, partly or wholly of spring metal, with a hook 50 upon its end. It may be forged all in one piece or formed in two pieces, as shown, and

when formed in two pieces that portion which is secured to the axle is preferably cast of malleable iron. It may be secured to the axle in any manner, but is preferably secured thereto 55 by clips, although bolts passing directly through it and the axle may be employed, if desired. When formed in two parts, the cast portion should be recessed and the spring portion should fit into this recess and be there 60 secured by a bolt, d.

A slot or a series of holes may be provided in one or the other of the pieces through which this bolt may pass, and the spring portion may thus be made adjustable on the cast 65 portion. This arrangement is of value when the supports are made and sold in quantities to be used with vehicles of various kinds, wherein the distances between the axle and the cross-bar to the shafts are not all the 70 same; but when the shaft-supports are made in the same factory with the vehicles they can of course be made of exactly the required length, and no adjustment is necessary. The blade or spring portion of this part is formed 75 with a slight twist or inclination, so that when the shafts are raised so that the part E has passed entirely beyond this part D it will on the return movement pass down on the opposite side from the hook, and thus the disengagement is effected without the application 80 of any power directly to the shaft-support; or, in other words, the engagement and disengagement be both effected by the vertical movement of the shafts themselves. 85

The support portion E is secured to the cross-bar B' and projects backwardly just a sufficient distance to engage with the point of the portion D when the shafts are raised, as shown most plainly in Fig. 3. The point 90 which comes into contact with the portion D is given a diagonal formation, as shown most plainly in Fig. 6, to assist it in passing the two sides of the point of said portion D as it is raised and lowered. It is forked or bifurcated and passes to both sides of the cross-bar B', where it develops into plates or washers, which take the place of those ordinarily used at this point, and also, preferably, has a third arm or portion which extends to above 100 the whiffletree, and through these several plates or washers the bolt or pin which se-

secures the whiffletree to the cross-bar extends, and this portion not only serves its own purpose, but takes the place of all other irons at this point.

5 Having thus fully described my said invention, what I claim as new, and desire to secure by Letters Patent, is—

1. The combination, with the axle and shafts of a vehicle, of a tongue-support made in two portions, one of which is secured to the axle and consists partly of a blade adapted to spring laterally and provided with a hook on one side of its point, and the other of which is secured to the shafts or cross-bar in such relation to the spring portion that when the shafts are raised it will pass up behind the hook and engage therewith, and when they are still farther raised will pass entirely beyond the spring portion, and upon their being lowered will pass down the other side, free from the hook, substantially as set forth.

2. The combination of the support portion D, secured centrally upon the vehicle-axle and embodying a blade adapted to spring laterally, having a hook upon its free end, and the support portion E, centrally secured upon the cross-bar to the shafts and having its point of a diagonal formation, whereby it is adapted to pass and engage with said hook when the shafts are raised to a certain point, and to entirely pass said support portion D when they are farther raised, and return on the other side as they are lowered, substantially as set forth.

3. The combination of the two portions D and E, forming a shaft-support, said portion E being also divided and passing astride the cross-bar to the shafts and formed to take the

place of the washers or irons usually used at that point, substantially as shown and described.

4. The combination of the two parts D and E, forming a shaft-support, the portion E being split or divided into three parts, one of which passes above the whiffletree, one between the whiffletree and the cross-bar, and the other below the cross-bar, whereby it serves, in addition to its purpose as a shaft-support, to take the place of the irons commonly used at this point, substantially as set forth.

5. The combination of the support portion D, consisting of two parts, one of which is recessed to receive the other and slotted for purposes of adjustment, a bolt by which they are secured together, clips by which the device as a whole is secured to the axle, a hook-point upon the free end thereof, the support portion E, having its engaging point formed diagonal with its general direction and secured to the cross-bar of the shaft in such relation that when the shafts are raised it will engage with the hook-point on the portion D, and divided or bifurcated at its point of union with the cross-bar, and thus adapted to pass on both sides of said cross-bar and take the place of the ordinary irons used at this point, substantially as shown and described.

In witness whereof I have hereunto set my hand and seal, at Martinsville, Indiana, this 23d day of August, A. D. 1888.

ANDREW J. WATSON, [L.S.]
